US00D359723S

United States Patent [19]

Itou et al.

[11] **Patent Number:** **Des. 359,723**[45] **Date of Patent:** ** Jun. 27, 1995

[54] **CONNECTOR FOR CHARGING ELECTRIC
MOTOR CAR**

[75] Inventors: **Hikaru Itou; Tsutomu Tanaka;
Fumiyoishi Tanigawa; Sho Miyazaki;
Shigekazu Wakata, all of Yokkaichi;
Toshiyuki Sekimori; Yasuyoshi
Fukao, both of Toyota, all of Japan**

[73] Assignees: **Sumitomo Wiring Systems, Ltd., Mie;
Toyota Jidosha Kabushiki Kaisha,
Aichi, both of Japan**

[**] Term: **14 Years**

[21] Appl. No.: **19,963**

[22] Filed: **Mar. 15, 1994**

[30] **Foreign Application Priority Data**

Sep. 17, 1993 [JP] Japan 5-28139

[52] U.S. Cl. **D13/146**

[57] **CLAIM**

The ornamental design for a connector for charging
electric motor car, as shown and described.

DESCRIPTION

FIG. 1 is a perspective view of the connector for charging
electric motor car according to the present invention;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

FIG. 1

FIG. 2

FIG. 3

FIG. 4

FIG. 5

FIG. 6

FIG. 7

UNITED STATES PATENT AND TRADEMARK OFFICE
CERTIFICATE OF CORRECTION

PATENT NO. : Des. 359,723

DATED : June 27, 1995

INVENTOR(S) : H. ITOU et al.

It is certified that error appears in the above-identified patent and that said Letters Patent is hereby corrected as shown below:

On the title page of the printed patent, in section [75], "Inventors:", "Yokkaichi" should be ---Yokkaichi-shi---.

On the title page of the printed patent, in section [75], "Inventors:", "Toyota" should be ---Aichi---.

Signed and Sealed this
Sixteenth Day of July, 1996

Attest:

BRUCE LEHMAN

Attesting Officer

Commissioner of Patents and Trademarks
